(57) **CLAIM**

The ornamental design for a cartomizer for a vaporizer, as shown and described.

DESCRIPTION

FIG. 1 is a front perspective view of a cartomizer for a vaporizer;

FIG. 2 is a top view of the cartomizer of FIG. 1;

FIG. 3 is a side view of the cartomizer of FIG. 1;

FIG. 4 is a front view of the cartomizer of FIG. 1;

FIG. 5 is a rear view of the cartomizer of FIG. 1; and,

FIG. 6 is a bottom view of the cartomizer of FIG. 1.

The broken lines in the drawings depict parts of the cartomizer for a vaporizer that form no part of the claimed design.
